UNITED STATES PATENT OFFICE.

CHARLES E. EMERY, OF BROOKLYN, NEW YORK.

TUBE-JOINT.

SPECIFICATION forming part of Letters Patent No. 310,264, dated January 6, 1885.

Application filed April 25, 1883. (No model.)

To all whom it may concern:

Be it known that I, CHARLES E. EMERY, of Brooklyn, Kings county, in the State of New York, (office in New York city,) have invented 5 certain new and useful improvements in the construction of joints between lengths of tube or pipe, or between pipes and their fittings, to form a continuous line of pipe; and I do hereby declare that the following is a full and 10 exact description of the invention.

I will first describe the invention as applied to the joining of the adjacent ends of two tubes to a stout connecting-ring of cast-iron, which incloses both and forms a rigid and reliable 15 junction. I form the interior of such ring with an internal rib at the mid-length and 20 about the nicely-turned end of each length of pipe against the said rib, one pipe end abutting against said rib on one side, and the other 25 pipe abutting against said rib on the opposite side. The interior of the ring is properly formed, each side of said rib to allow a tight junction of the pipe therewith to be produced by expanding. I propose to use the expander 30 known as "Dudgeon's," with or without certain modifications which I have invented and will make the subject of a separate application for patent. I form the outside of the junction-ring with two ribs or re-enforces extending 35 around in the planes where the greatest pressure is exerted by the expander.

The accompanying drawings form a part of this specification, and represent what I consider the best means of carrying out the invention.

Figure 1 is a central longitudinal section showing the tube-joint complete before the expander is removed. Fig. 2 is a corresponding cross-section on the line $x-x$ in Fig. 1. Fig. 40 3 is a central longitudinal section through a modification. Fig. 3^a is a longitudinal section through another modification.

Similar letters of reference indicate like parts in all the figures.

45 A is a length of thin iron tubing, which I will assume to be of considerable diameter—say from six to twelve inches—and of only a quarter of an inch thickness. It may form the last of a series previously joined.

50 B is another similar tube to be joined to A to form a continuous line of pipe.

C is a stout ring of cast-iron or other suitable material, in which both tubes A and B are to be received and rigidly and tightly confined.

55

C' C' are external ribs.

C² is an internal rib.

C³ C⁴, C⁵ C⁶ are swells or broad shallow ribs extending around in the position represented. The spaces between C³ and C⁴ are marked $e-e$, 60 and are smoothly rounded, as shown in Fig. 1. I form the junction by the aid of a device analogous to a Dudgeon expander operated by a mandrel having a tubular extension in the line of the axis of the tube, and which is operated from the outside.

65 D is the mandrel, and D' a portion of the extension therefrom.

The rollers are mounted within a housing or frame, K, which is connected by the ring 70 J and screw-pins j to a ring, I', to which is rigidly connected a stationary tube, I, which is mounted around the mandrel D and its extension D', and extending the whole length of the tube B.

75

I attach much importance to the internal rib, C², receiving the ends of the tubes A and B. It serves as a gage to hold the tubes in place, and also as a firm abutment to relieve the oblique surfaces of the expanded parts 80 from strain due to end-thrusts on the pipes.

I propose to use these joints in steam-heating where there is considerable compressive force exerted on the several lengths of pipe by the pressure of the steam in expansion-joints of 85 larger diameter which are introduced at frequent intervals. I also attach importance to the external webs or ribs, C', and to their location.

They re-enforce the ring C at the points where the great strain is impressed in 90 the act of expanding. By this construction a relatively light ring, C, may serve to resist the great expansive force impressed in the act of setting the tube and continued by the presence of the expanded tube on the interior, 95

and the high pressure of steam or other fluid to which it may be subjected. The inner surface of the ring or rings C is formed with ridges C³ C⁴, alternating with cavities or recesses, into which latter the metal of the tubes 100 is forced by the powerful distending force exerted by the rollers. The rollers also give a

general conical form to the tube ends, as shown. When the tubes are firmly set, the abutment of the end of each tube squarely against the internal ring, C², holds the parts 5 strongly in position against displacement relatively to each other in one direction, and the conical form of the tube end bearing against the general inner surface of the ring or rings C efficiently resists displacement of the parts 10 relatively to each other in the opposite direction. The ring or rings C are longer than their bearings on the tubes A and B. A considerable calking-space, c', is provided between each tube and the ring. This may be 15 left empty, and the joint may serve successfully; but I prefer in most cases to utilize this space as follows: I provide a wrought-iron ring, T, matching loosely around each tube A and B, of such thickness as may be easily forced into the space c' around the tube. Before bringing the ring T into position I crowd into the space c' a paste or cement, E, composed of iron filings or turnings, or both, wetted with a solution of sal-ammoniac in water. 20 A quantity of this paste is calked into the space, then the ring T is brought into position, and more paste applied and calked. The resulting rust-joint conduces greatly to the tightness of the joint, and also to the stiffness with which the two tubes are connected 25 to the ring or rings C, and consequently to each other. In case the tubes are liable to be deflected, so as to greatly strain the joint after the latter is made, I can delay the forming of 30 the rust-joint until the tubes are in their final position. Then sufficient space being left for access with proper tools, the ring T and the paste are brought into position and calked tightly into the recess, with the effect to mechanically sustain the parts firmly in their 35 position and to effectually prevent any possible leak of steam or other fluid through the joint. The iron ring T imparts an increased stability and stiffness to the joint. 40

In Fig. 3 I have shown the ends of the respective tubes expanded into separate rings instead of different parts of the same ring. These two rings are marked by the same letter as the single ring in the other figures. 45

The flanges C' contribute to the stiffness and strength of the ring, although not situated, like the ribs C, directly in the plane of the distending force exerted by the expansion. This figure shows the application of a portion 50

of my invention, the flanges being secured together by bolts or other approved means. 55 Packing may be introduced between the flanges. In this form of the invention, as in the other, the internal ribs, C', receive the abutting force of the tubes A B. They relieve 60 the oblique expansion-surfaces from the strain due to the end-thrust of the tubes.

The tool by which the joint is formed will be made the subject of a separate application for patent. 65

Variations may be made in many of the details without departing from the principle or sacrificing all the advantages of the invention. The whole cavity c' may be filled with corrosive cement instead of employing the iron 70 ring T.

I claim—

1. In a tube-joint, in combination with the tubes A B, a coupling-ring having an internal annular rib, c², against which the ends of 75 the said pipes abut, and having internal annular rounded recesses, c, into which the material of the pipes is forced by expanding-rollers, as and for the purposes set forth.

2. In a tube-joint, the combination, with 80 the pipes A B, of a coupling-ring having internal annular recesses, as c, into which the pipe material is forced by expanding-rollers, and having re-enforcing external ribs to correspond with such recesses and withstand the 85 pressure, the pipes A B abutting against an internal annular rib formed in the coupling, as set forth.

3. The ring C, having the re-enforces C' on the exterior and the internal recesses, c, and 90 central internal abutting-rib, C², in combination with the two tubes A B, and joined tightly thereto by the expansion of the tubes, all substantially as and for the purposes herein specified. 95

4. The ring C, having the calking-spaces c', in combination with the tubes A B, the paste E, and rings T, as and for the purposes set forth.

In testimony whereof I have hereunto set 100 my hand, at New York city, N. Y., this 23d day of April, 1883, in the presence of two subscribing witnesses.

CHAS. E. EMERY.
